MARSHALL BURNS LLOYD, OF MENOMINEE, MICHIGAN, ASSIGNOR, BY MESNE ASSIGNMENTS, TO THE ELYRIA IRON & STEEL COMPANY, OF ELYRIA, OHIO, A CORPORATION OF OHIO.

SURFACE-FINISHED TUBE.

1,178,813.

Specification of Letters Patent. Patented Apr. 11, 1916.

Original application filed August 7, 1912, Serial No. 713,851. Divided and this application filed September 19, 1913. Serial No. 790,775.

To all whom it may concern:

Be it known that I, MARSHALL B. LLOYD, a citizen of the United States, and a resident of Menominee, county of Menominee, and 5 the State of Michigan, have invented a certain new, useful, and Improved Surface-Finished Tube, of which the following is the specification.

My invention relates generally to the tube 10 making industry and has particular reference to the surface finish or polish of metal tubing.

The general object of my invention is to 15 provide tubing which shall present a pleasing appearance, which shall contain an exterior surface well adapted to prevent rusting and corrosion of the tube, and which shall be capable of rapid and economical production.

20 My invention consists generally in the novel article of manufacture hereinafter described and claimed and will be more readily understood by reference to the accompanying drawings in which I have depicted the 25 novel tubing and the stages of its production.

In the drawings Figure 1 is a perspective view of a portion of rolled strip metal such as is much used in the formation of welded tubing. Fig. 2 is a somewhat enlarged view showing the strip converted into a tube; and Fig. 3 is a perspective view of the tube in the surface finished or highly polished condition.

35 Tubing is used in many industries where a pleasing appearance or finish is desirable, but which require tubing of comparatively low cost. Hence such processes as nickelizing, copper finishing, and the like are prohibitive. There are other reasons why a finished or highly polished tube is desirable for 40 many uses, one of which is that tubing formed by any of the known processes, when it emerges from the forming mechanism is 45 rough and somewhat abraded, and, therefore, particularly susceptible to rust. It is my purpose to provide, as an article of manufacture, tubing combining the desirable features above enumerated, and which 50 shall cure the defects present in the tube as formed by the usual tube forming processes.

This application is related to and is a divisional part of my pending application, Serial No. 713,851, filed August 7th, 1912, for

process of reducing and surface finishing 55 metal tubes, rods and the like. The process there described and the mechanism shown for practising that process are well adapted to produce my improved surface finished or polished tube, and will be found 60 of great assistance in the rapid and economical manufacture of this article.

Referring to the drawings, 1 represents a strip of rolled metal such as is much used in the formation of welded, brazed, and 65 drawn tubing. In the process of forming the strip metal, which consists in passing a billet through a series of reducing rolls, the metal is given a grain which runs longitudinally of the strip. For clearness of 70 illustration I have depicted the grain by a plurality of longitudinal lines 2. The strip metal 1 is passed through suitable shaping mechanism wherein it assumes the shape of a tube and then by passing the tube through 75 welding or other mechanism its seam edges are joined, presenting finally the appearance of a seamless tube, as illustrated in Fig. 2. The shaping of the strip metal into tubular form does not materially alter the 80 grain because the forming mechanism applies substantially the same general forces to the metal as the mechanism which originally produced the strip. The grain, therefore, runs longitudinally of the tube both 85 within and without, as shown. Tubing which is formed by the so-called seamless drawing process also presents a longitudinal grain. Therefore, Fig. 2 may represent either a drawn tube or a welded tube, and 90 when I refer to it as a seamless tube the term should be construed to include a tube which has been welded; one which has been produced by drawing, or one which has been produced by any other process, as I am not 95 here concerned with the initial formation of the tube, but instead this application has to do only with finished or polished tubing, without special regard to the method by which the rough tubing is produced.

100 For the reasons stated, the tube as shown in Fig. 2 is usually rough and slightly abraded and easily susceptible to rust. Even if the tubing is ultimately to be painted it is desirable to have a finish of some 105 sort upon the tube to prevent excessive rusting between the time of the manufacture and the time of use, which, in the ordinary

course of business, is a considerable period. Generally it is sufficient to finish only the exterior of the tube, as that surface is the one which is most susceptible to rust and because it is the visible surface. I find that by changing the grain upon the surface of the tube and by making a circumferentially fine grain thereon, that I can produce a surface finish or polish which will be effective for the uses intended and which, at the same time, can be rapidly and economically produced. I have indicated in Fig. 3 a tube embodying my invention with the outer surface thereof finished or polished, and the inner surface left in its initial or unfinished state. The grain 2 upon the inner surface of the tube runs longitudinally thereof while the grain 3 upon the outer surface runs circumferentially of the tube. I have indicated the grain 3 as extending slightly into the tube, that is, it appears as a surface skin, as will be seen by reference to the end portion of the tube, indicated by the numeral 4.

In order that the structure of the tube may be better understood, I shall here describe briefly one process for making the product which I find to be highly successful. The unfinished tube in the condition shown in Fig. 2 is placed in mechanism which firmly clamps it and holds it against rotation. The tube in this condition is then passed through mechanism containing a plurality of high speed rotating rolls which act upon the outer portion thereof, and impart to the outer surface of the tube a thin skin or layer grain extending circumferentially of the tube. By providing the rolls

of hardened steel with highly finished surfaces and by providing a suitable lubricant, a tube, such as emerges from the forming mechanism, can be highly finished by a simple pass through the skin forming or polishing mechanism; that is, by one operation, a fine circumferential surface grain of desired thickness can be formed. The cost of providing this finish is slight. It serves admirably to prevent the tube from rusting, and produces a finish which approximates that of a nickel tube. Any roughness or abrasion caused by the tube forming mechanism is entirely obliterated, and where the tube has a welded seam, the seam is made invisible. Strictly speaking my novel tubing is the product of the process and apparatus shown in said prior application Serial No. 713,851. It was never produced until that process was invented and I know of no other way in which it may be produced.

I claim:

A new article of manufacture comprising a metal tube chiefly characterized by the longitudinal trend or graining of the metal, but presenting a brilliantly smooth minor portion, constituting an outer skin, in which the metal has a distinguishable circumferential trend.

In testimony whereof, I have hereunto set my hand, this 16th day of Sept., 1913, in the presence of two subscribing witnesses.

MARSHALL BURNS LLOYD.
